UNITED STATES PATENT OFFICE.

FRANCIS W. JACKSON, OF EAST ORANGE, NEW JERSEY.

PHOTOGRAPHIC-PLATE HOLDER.

SPECIFICATION forming part of Letters Patent No. 277,737, dated May 15, 1883.

Application filed February 3, 1883. (No model.)

To all whom it may concern:

Be it known that I, FRANCIS W. JACKSON, a citizen of the United States, residing at East Orange, in the county of Essex and State 5 of New Jersey, have invented certain new and useful Improvements in Photographic-Plate Holders; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 This invention relates more particularly to that portion of photographic apparatus known as "dry-plate holders," and has for its object an improved method of constructing said holders, which will be hereinafter fully set forth, 20 and finally embodied in the claims.

In the drawings, in which similar letters of reference indicate like parts in each of the several figures, Figure 1 is a plan view of a 25 plate-holder; and Fig. 2 is a sectional view of the same, taken through line x.

The purpose of these holders is well understood by those skilled in the art.

The dry-plate system of photography, as is well known, has superseded to a great extent 30 the wet-plate system, but more particularly for out-of-door photography, or "viewing," as it is called. The simplicity of the new process has thrown the art open to the amateur, and its popularity is rapidly increasing.

35 The defect in the plate-holders up to the present time has been that there were no permanent means provided to designate upon the holders which plates had been exposed, and innumerable errors of exposure have been 40 made through this defect. It has been customary with some to paste paper upon the slides of the plate-holders, on which to make memoranda; but this plan is very unsatisfactory. The moistening of the slides injures 45 them, and the paper, if it does not come off accidentally, needs frequent renewing. The advantage of having a permanent face on which to write the details of the exposure of the plate, the view taken, &c., will therefore 50 be manifest to amateur or professional photographers. This object I accomplish either by coating the slides *a'*, or any part of the frame *b*, of plate-holder, or both, with mineral, metallic, or rubber paint, or enamel or silicate,

or paper, or any other substance coated with 55 silicate or analogous materials, or by constructing the slide or frame of the holder of any materials—such, for instance, as celluloid or rubber—compounded with silicate or analogous materials, so as to form a surface capable of being written upon and of having the writing erased at pleasure an indefinite number of times without impairing or injuring the said surface. By thus constructing these articles every facility is afforded for preserving 65 with each view the data referring to it.

I am aware that plate-holders, &c., have been made heretofore of plastic and other materials—such as rubber, celluloid, paper, papier-maché, wood, wood pulp, card-board, 70 metal, &c.—and also by attaching together a number of layers of materials; but never, so far as I am aware, have they been provided permanently with a surface to admit of being written upon and of the writing being erased 75 without injury to said surface, as herein contemplated.

Having thus described my invention, what I claim as new, and wish to secure by Letters Patent, is—

1. As a new article of manufacture, a dry-plate holder for photographic purposes, having the frame or slide, or both, provided with a surface of silicate or other material which will admit of being written upon and having the 85 writing erased without injury to said surface, as and for the purposes herein set forth.

2. In a dry-plate holder for photographic purposes, the combination, with the frame thereof, of a slide having a surface of silicate 90 or other material which will admit of being written upon and the writing erased without injuring the said writing-surface, as set forth.

3. In a dry-plate holder for photographic purposes, the combination of a frame with a 95 slide constructed of such material as celluloid and prepared rubber, having the outer or exposed portion thereof prepared or coated with materials, as herein described, so as to admit of being written upon and of the writing being erased an indefinite number of times without impairing said surface, as set forth.

In testimony that I claim the foregoing I have hereunto set my hand this 30th day of January, 1883.

Witnesses: FRANCIS W. JACKSON,

OLIVER DRAKE,
F. F. CAMPBELL.
